(57) **CLAIM**

The ornamental design for display storage apparatus for sports equipment, as shown and described.

DESCRIPTION

FIG. 1 is a front elevation view of the display storage apparatus for sports equipment illustrating my new design, with a ball shown in broken lines for illustrative purposes only and forming no part of the claimed design;

FIG. 2 is a front elevation view thereof;

FIG. 3 is a left side elevation view thereof, with a ball shown in broken lines for illustrative purposes only and forming no part of the claimed design, the right side elevation view being a mirror image thereof;

FIG. 4 is a left side elevation view thereof, the right side elevation view being a mirror image thereof;

FIG. 5 is a top plan view thereof;

FIG. 6 is a bottom plan view thereof;

FIG. 7 is a front perspective view thereof;

FIG. 8 is a front elevation view of a second embodiment of my claimed design, with a ball shown in broken lines for illustrative purposes only and forming no part of the claimed design;

FIG. 9 is a front elevation view thereof;

FIG. 10 is a left side elevation view thereof, with a ball shown in broken lines for illustrative purposes only and

forming no part of the claimed design, the right side elevation view being a mirror image thereof;

FIG. 11 is a left side elevation view thereof, the right side elevation view being a mirror image thereof;

FIG. 12 is a top plan view thereof;

FIG. 13 is a bottom plan view thereof;

FIG. 14 is a front perspective view thereof;

FIG. 15 is a front elevation view of a third embodiment of my claimed design, with a ball shown in broken lines for illustrative purposes only and forming no part of the claimed design;

FIG. 16 is a front elevation view thereof;

FIG. 17 is a left side elevation view thereof, with a ball shown in broken lines for illustrative purposes only and forming no part of the claimed design, the right side elevation view being a mirror image thereof;

FIG. 18 is a left side elevation view thereof, the right side elevation view being a mirror image thereof;

FIG. 19 is a top plan view thereof;

FIG. 20 is a bottom plan view thereof;

FIG. 21 is a front perspective view thereof;

FIG. 22 is a left side elevation view of a fourth embodiment of my claimed design, with a ball and bat shown in broken lines for illustrative purposes only and forming no part of the claimed design, the right side elevation view being a mirror image thereof;

FIG. 23 is a left side elevation view thereof, the right side elevation view being a mirror image thereof;

FIG. 24 is a front elevation view thereof, with a ball and bat shown in broken lines for illustrative purposes only and forming no part of the claimed design;

FIG. 25 is a front elevation view thereof;

FIG. 26 is a top plan view thereof;

FIG. 27 is a bottom plan view thereof;

FIG. 28 is a front perspective view thereof;

FIG. 29 is a front elevation view of a fifth embodiment of my claimed design, with a ball shown in broken lines for illustrative purposes only and forming no part of the claimed design;

FIG. 30 is a front elevation view thereof;

FIG. 31 is a left side elevation view thereof, with a ball shown in broken lines for illustrative purposes only and forming no part of the claimed design, the right side elevation view being a mirror image thereof;

FIG. 32 is a left side elevation view thereof, the right side elevation view being a mirror image thereof;

FIG. 33 is a top plan view thereof;

FIG. 34 is a bottom plan view thereof; and,

FIG. 35 is a front perspective view thereof.
